VALVE FOR AUTOMOBILE BODY HEATERS

Edmund Ludlow, Columbus, Ind., assignor to
Arvin Industries, Inc., a corporation of Indiana

Application July 8, 1949, Serial No. 103,653

1 Claim. (Cl. 251—17)

This invention relates to automobile-body heating and ventilating systems, and more particularly to a valve and valve-operating means for controlling air flow in such a system. It is an object of the invention to provide a simple and inexpensive valve and valve mounting and to associate with such valve an operating means of simple construction adapted for operation by a conventional Bowden wire extending to a remote point.

In carrying out the invention in its preferred form I employ a valve in the form of a vane which is pivotally mounted in a housing or conduit, desirably on an axis displaced from the plane of the vane. The vane is provided with an ear which extends across the axis of mounting and is in turn provided with a non-circular opening to receive slidably a valve-operator movable longitudinally of itself along the axis of valve mounting. The valve-operator is of non-circular cross-section corresponding to the shape of the opening in the ear and is slidably received in the wall of the conduit or valve-housing in an opening which is also non-circular, whereby the operator, as it moves longitudinally of itself, remains in a constant condition of orientation relative of the valve-axis. That part of the operator which moves through the ear as the operator moves longitudinally is twisted, with the result that longitudinal movement of the operator causes the valve to swing about its axis. The operator may be moved through any convenient means, but is adapted for control by a Bowden-wire extending to a remote control point.

The accompanying drawing illustrates the invention: Fig. 1 is a vertical section on the line 1—1 of Fig. 2 through an automobile-body heater in which my invention has been embodied; Fig. 2 is a vertical section on the line 2—2 of Fig. 1; Fig. 3 is a fragmental plan view of the heater with portions of the valve housing broken away to illustrate the construction more clearly; Fig. 4 is a fragmental vertical section on the line 4—4 of Fig. 3; and Fig. 5 is a fragmental isometric view illustrating a detail of construction.

The heater illustrated in the drawing, which is of a type more fully illustrated and described in my copending application Serial No. 85,367 filed April 4, 1949, comprises a casing 10 having an air-admitting opening 11 in its lower wall. Within the casing there is disposed an electrical motor 12 arranged to drive two air-impelling elements, one a conventional propeller type fan 13 and the other a blower-rotor 15 located within a blower scroll-housing 16. Associated with the air-ad-

mitting opening 11, there is a heat-exchanging core 18, adopted for connection into the coolant circulating system of the automobile engine, by means of which air entering the casing and the passing to the fan 13 and blower-rotor 15 is warmed. The scroll housing 16 has an outlet neck 20 disposed to discharge upwardly into a housing 21 secured to the upper wall of the casing 10, conveniently near a front corner thereof. The housing 21 is provided in its upper wall with a pair of outlet nipples 22 adapted for connection to flexible conduits extending to remote points, as to defroster nozzles located adjacent the automobile windshield. The housing 21 continues rearwardly beyond the outlet-neck 20 of the blower-housing 16 and is provided in its outer side wall with an air outlet opening 24. The rear wall and the top wall of the housing 21 may continue outwardly beyond the opening 24, as indicated at 25 and 26 in Fig. 3, to direct air discharged through the opening 24 toward the feet of the driver of the automobile.

It is the purpose of my invention as embodied in the heater described to provide a valve and a valve operating means adjustable to divide between the opening 24 and the outlet nipples 22 the heated air which is discharged into the housing 21 through the outlet-neck 20 of the blower-housing 16. For this purpose, there is provided within the housing 21 a flap valve, designated in its entirety by the reference numeral 28, which is pivotally mounted for swinging movement between the full-line and dotted-line positions indicated in Fig. 4. In its full-line position, the valve 28 extends vertically across the housing 21 ahead of the opening 24 and restricts the flow of air to such opening. In its dotted-line position, the valve is interposed between the outlet neck 20 and the discharge nipples 22 and hence restricts the supply of air to the discharge nipples. It is usually not essential that the valve effect a complete closure in either of its limiting positions of adjustment; but substantially complete closure is desirable when the valve is in its vertical position, because of the pressure required to force air through conduit connected to the nipples 22.

The particular valve shown in the drawing comprises a pair of sheet-metal stampings 29 and 30 between which there is clamped a strip of felt or similar material 31 providing an effective seal and minimizing the possibility of rattling. The stamping 30, which lies at the front face of the valve, is provided at its ends with forwardly extending ears 32 and 33 and near its center with a third ear 34, all such ears being

aligned. The ear 33 and the adjacent side wall of the housing 21 are provided with aligned openings for the reception of a rivet or equivalent element 35 affording a pivotal connection. The ear 32 is provided with an opening rotatably receiving (see Fig. 53) a bushing 36 having a flange 37 disposed between the ear 32 and the adjacent side wall of the housing 21. The bushing 36, the adjacent side wall of the housing 21, and the intermediate ear 34 are provided with aligned, non-circular openings adapted to receive slidably a valve-operator 40 having a cross-sectional shape similar to the shapes of the openings which slidably receive it. Conveniently, the operator 40 is a metal strip or bar of rectangular cross section. Adjacent the ear 34, the operator 40 is twisted through an angle corresponding to the angle through which the valve 28 is to swing. As a result, by moving the operator longitudinally of itself to cause its twisted portion to pass through the ear 34, the valve is swung from one extreme position to the other. In so swinging, the valve pivots about the rivet or pin 35 and the bushing 36.

For the purpose of moving the operator 40 longitudinally of itself, I preferably employ a Bowden wire 42 which is connected to the outer end of the operator 40 in any convenient manner and which extends through the conventional sheath 43 to a conveniently located remote control point. That end of the Bowden-wire sheath 43 adjacent the operator 40 may be anchored in fixed position by attachment to a bracket 45 secured to and projecting outwardly from the housing 21.

In the particular arrangement illustrated in the drawing the operator 40 is twisted between the ear 34 and the bushing 36, and outward movement of the operator moves the valve 28 to its vertical position, as indicated in full lines in Fig. 4, such outward movement of the operator being limited by a pin 46 which extends through the operator in position to engage the intermediate ear 34 on the valve. As the operator is moved inwardly of the housing 21 from the position shown in the drawings, its twisted por-

tion 47 passes through the non-circular opening in the ear 34 and rotates the valve from the full-line to the dotted-line position of Fig. 4.

It is to be understood that the particular arrangement illustrated in the drawing is shown merely by way of example and that my invention can be used in other situations for adjusting a valve adapted to control the flow of air through housings or conduits of a wide variety of forms.

I claim as my invention:

In a device of the type described, a hollow fluid-conducting member, a valve for controlling fluid flow through the hollow member, said valve comprising a plate having aligned ears at its opposite ends and an intermediate ear between and aligned therewith, means co-operating with the end ears for pivotally supporting the valve from and within the housing, an extended valve operator coincident with and movable along the axis of the valve's mounting, said intermediate ear having a non-circular opening, said operator having a twisted portion of non-circular cross-section slidably received in said opening, and means for preventing rotation of said valve operator as it moves along said axis.

EDMUND LUDLOW.
